UNITED STATES PATENT OFFICE.

THOMAS R. McDOWALL AND SAMUEL G. PERKINS, OF LONDON, ENGLAND.

GLAZING-BAR.

1,229,631.

Specification of Letters Patent. Patented June 12, 1917.

Application filed February 17, 1915. Serial No. 8,777.

To all whom it may concern:

Be it known that we, THOMAS REGINALD McDOWALL and SAMUEL GREGORY PERKINS, subjects of the King of Great Britain, residing at 14 Uptall street, Myatt's Park, London, and 27 Twilly street, Wandsworth, London, England, respectively, have invented new and useful Improvements in Glazing-Bars, of which the following is a specification.

This invention relates to improvements connected with glazing bars or the like and is more particularly for use in connection with reinforced concrete bars or the like.

The object of our invention is to combine a lead or like flashing with a glazing bar or the like in such manner that it can be readily detached from the said bar when necessary for making repairs thereto, or renewal of the glass, the said flashing being secured to the bar without the employment of bolts and nuts or similar securing means, thus avoiding any slotting or holing of the flashing and the bar.

Referring to the drawings:—

Figure 1 is a sectional perspective view of one construction of this invention, showing the fixing strip in position in the glazing bar, but the lead flashing has not yet been bent on to the glass.

Fig. 2 is a similar view to Fig. 1, but illustrating the flashing in position, as in use.

Fig. 3 is a perspective view of one form of holding strip.

Fig. 4 is a modification.

Referring first primarily to Figs. 1, 2 and 3, the reinforced concrete glazing bar 1 is formed of any suitable section and provided with any suitable reinforcements, such as wires 2, the reinforcement being completely embedded in the concrete so as to avoid any deleterious action thereon by the atmosphere. The glazing bar has the usual condensation slots or grooves 3 therein, and shoulders 4 upon which the glass 5 rests.

A glazing bar constructed according to this invention is provided on its upper surface with a longitudinal groove or slot 6 of a suitable depth and shape to receive the lead or other flashing 7 and a fixing strip or strips 8. The section of the strip 8 depending upon the shape of the groove or slot 6 wherein it is partly contained. When the groove or slot 6 has parallel sides as seen in Figs. 1 and 2, the width of the slot is

formed just sufficient to receive the lead flashing and the strip 8 as a driving fit, so that when the strip has been forced or driven into position as seen in Fig. 1, it will effectively retain the flashing 7 within the slot 6. The strip 8 is made of metal, wood or other suitable material and may be formed in one continuous length or in a series of short lengths as desired. When the flashing 7 has been secured by the fixing strip in the position seen in Fig. 1, the flashing is bent over to contact with the glass 5, and thus the glass is firmly secured in position without the employment of bolts, nuts, clips or other similar means, and avoiding also any drilling or screwing.

When it is necessary to make repairs to the glass or flashing, the strip 8 is removed from the slot 6 and the damaged or worn parts repaired or removed quickly and without resource to skilled labor.

In the modification illustrated by Fig. 5 of the drawings we employ a zinc or other trough or channel 11 within the longitudinal slot 6, between the concrete and the lead flashing 7, the purpose of the said trough or channel 11 being to permit of a more ready insertion and removal of the flashing when necessary, the trough or channel preventing the roughened surface of the concrete contacting with the lead or other flashing at that part of its area where it is forced or driven into the slot 6.

We do not limit our invention to the construction illustrated by the accompanying drawings as obviously many other constructions could be effected within the scope of the claims hereto appended.

We have described our invention more particularly with reference to concrete or reinforced concrete glazing bars but it is obvious that it may be applied to glazing bars made from wood or metal or other suitable materials.

It will be obvious that our invention might with equal facility be applied to purlins, ridges, hips or framings.

What we claim as our invention is:—

1. In a concrete or like plastic glazing or analogous bar having a groove therein the sides of which are substantially parallel to one another, the combination of a sheet material flashing partly disposed within said groove and partly external thereto said external part being adapted to secure the glazing light upon the bar, and a substantially

- parallel sided fixing strip adapted to maintain the said flashing on the bar, said strip being finally introduced into said groove and initially removed therefrom.
5. 2. In a concrete or like plastic glazing or analogous bar having a groove therein the sides of which are substantially parallel to one another, the combination of flashing of sheet material partly disposed within said groove said flashing comprising a strip of flexible metal having flanged external portions adapted to contact with the glazing light and maintain same in position, and a substantially parallel sided fixing strip adapted to maintain the said flashing on the bar, said strip being finally introduced into said groove and initially removed therefrom.
3. In a concrete or like plastic glazing or analogous bar having a groove therein the sides of which are substantially parallel to

one another, the combination of a metal trough disposed within said groove for the purpose of facilitating the insertion and removal of the flashing, a flexible metal flashing partly disposed within said trough and having flanged portions external to said trough to contact with the glazing light and maintain same in position, and a substantially parallel sided fixing strip adapted to maintain the said flashing on the bar, said strip being finally introduced into said trough and initially removed therefrom.

In testimony whereof we have signed our names to this specification in the presence of two subscribing witnesses.

THOS. R. McDOWALL.
SAMUEL G. PERKINS.
